(57) **CLAIM**

The ornamental design for a knife, as shown and described.

DESCRIPTION

FIG. 1 is a front elevational view of the knife in accordance with an embodiment of the design;

FIG. 2 is a rear elevational view of the knife illustrated in FIG. 1;

FIG. 3 is a top plan view of the knife illustrated in FIGS. 1-2;

FIG. 4 is a bottom plan view of the knife illustrated in FIGS. 1-3;

FIG. 5 is a right side elevational view of the knife illustrated in FIGS. 1-4;

FIG. 6 is a left side elevational view of the knife illustrated in FIGS. 1-5; and,

FIG. 7 is a right side elevational view of the knife illustrated in FIGS. 1-6, showing the knife in a folded position. The broken line portions of the drawings are for illustrative purposes only and form no part of the claimed design.
